[57] **CLAIM**

The ornamental design for a resilient foot support, as shown.

DESCRIPTION

FIG. 1 is a top, front and right side perspective view of a resilient foot support showing my new design;

FIG. 2 is a left side elevational view;

FIG. 3 is a rear elevational view;

FIG. 4 is a front elevational view;

FIG. 5 is a top plan view; and,

FIG. 6 is a bottom plan view.

The straps of FIGS. 2-6 have been shown in an open condition.
